UNITED STATES PATENT OFFICE.

JOHN A. SWITZER, OF PARR, INDIANA.

BOLT HOLDER.

Application filed March 27, 1923. Serial No. 628,055.

To all whom it may concern:

Be it known that I, JOHN A. SWITZER, a citizen of the United States, residing at Parr, in the county of Jasper, State of Indiana, have invented certain new and useful Improvements in Bolt Holders; and I do hereby declare the following to be a full, clear, and exact description of the invention, such as will enable others skilled in the art 10 to which it appertains to make and use the same.

This invention relates to tools and particularly to tools for holding bolts while the nuts are being screwed on or off.

15 One object of the invention is to provide a device of this character which is particularly adapted for holding the bolts of an engine crank-case, and which will remain in position on the head of the bolt 20 while the operator uses both hands to manipulate the wrench by means of which the nuts are turned on or off.

Another object is to provide a device of this character which will bear against a 25 portion of the crank-case so that the bolt and tool will remain stationary while the nut is being turned.

Other objects and advantages will be apparent from the following description when 30 taken in connection with the accompanying drawing.

In the drawing:

Figure 1 is a perspective view of the bolt holding tool.

35 Figure 2 is a side elevation of the joined portions of the crank-case of an engine, showing the tool engaged with the head of the bolt.

Figure 3 is a view looking upwardly at 40 the parts shown in Figure 2, showing the manner in which the tool engages with the head of the bolt and with the side of the crank-case.

Referring particularly to the accompanying drawing, 10 and 11 represents the flanges 45 of the upper and lower portions 12 and 13, of the crank-case of an automobile engine, with the bolt 14 disposed upwardly therethrough and having the nut 15 on the upper 50 end.

The tool comprises a pair of members A and B, the former of which is provided with a handle shank 16, at one end, and a jaw 17 at its other end, the inner face of 55 the shank 16 having a shoulder 18 for a purpose which will presently appear. In-

wardly of the jaw 17 the member A is formed with an enlargement 19 the outer end of which is bifurcated at 20, with the furcations formed with transversely alining openings 21 to receive the pivot pin or bolt 22.

The member B is formed with the handle shank 23, at one end, and the jaw 24, at the other end, the latter for cooperation with the jaw 17 to grip the head of the bolt 14 therebetween, as clearly seen in Figure 3, of the drawing. The inner face of the shank 23 is formed with a shoulder 25, and engaged on the said shoulder, and the shoulder 18, are the legs of the V-shaped spring 26. The opposite sides of the jaw portion of the member B are transversely grooved, as at 27, for the reception of the furcations of the bifurcation 20, and also receives the pivot 22 therethrough, whereby the members A and B are pivotally connected together. The spring 26 normally urges the shank 16 and 23 away from each other, and the jaws 17 and 24 toward each other, with the result that the head of the bolt will be firmly gripped therebetween, and remain so positioned without the aid of the operator. One of the shanks is arranged to rest against the side of the lower portion 13 of the crank-case so that when a wrench is applied to the nut, on the upper end of the bolt, and the nut turned, any tendency of the bolt to turn will be prevented. Thus the operator may 30 use both hands to manipulate the wrench, and be assured that the bolt will not turn.

The mutually adjacent faces of the jaws 17 and 24 are disposed in approximately parallel relation so that when engaged with the opposite faces of the head of the bolt, they will stand parallel. Also, the opposite side walls 27', of the grooves 27, serve to limit the opening movement of the jaws, with the result that the nut cannot rotate between the jaws. Any tendency of the bolt to turn will cause the tool to be swung so that one of its shanks will engage the side of the crank-case, and thereby check such movement of the bolt.

To apply the device, it is only necessary to press the shanks toward each other to separate the jaws, when the tool is slipped onto the head of the bolt and the shanks released. The spring 26 will urge the jaws into firm engagement with the bolt head, thus permitting the operator to release his hold from 110

the tool, whereby the tool will maintain itself in bolt gripping position.

What is claimed is:

- A bolt holding tool for use in connection
5 with an engine crank-case and comprising
a pair of pivotally connected bolt head
gripping jaws and operating shanks, said
shanks being arranged to bear against the
side of the crank-case to prevent turning of
10 the tool under the turning tendency of the
bolt, and having cooperating stop means for
limiting the opening movement of the jaws
beyond a parallel position, the inner faces

of the outer ends of the shanks having shoulders, and a V-shaped spring between the
15 shanks and having its legs retained by said
shoulders for urging the jaws into gripping
engagement with the head of the bolt and
for supporting the tool in such position
without external aid.

20

In testimony whereof, I affix my signature, in the presence of two witnesses.

JOHN A. SWITZER.
